Specification for Design.

Patented Feb. 16, 1915.

Application filed January 4, 1915. Serial No. 532. Term of patent 3½ years.

To all whom it may concern:

Be it known that I, JOHN J. NASH, a citizen of the United States, residing in Waterbury, in the county of New Haven and State of Connecticut, have invented a new original, and ornamental Design for a Shade-Holder, of which the following is a specification, when taken in connection with the accompanying drawing.

In the drawing, Figure 1 is a top plan view of a shade holder embodying my design, and Fig. 2 is a side elevation of the same.

What I claim is:—

The ornamental design for a shade holder, substantially as shown.

JOHN J. NASH.
